(74) *Attorney, Agent, or Firm* — Dentons US LLP

(57) **CLAIM**

The ornamental design for shoe jewelry, as shown and described.

DESCRIPTION

FIG. 1 is a first embodiment of a front perspective view of shoe jewelry showing my new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a front perspective view thereof, shown in a used condition on a shoe shown in broken lines;
FIG. 9 is a second embodiment of a front perspective view of shoe jewelry showing my new design;
FIG. 10 is a front elevation view thereof;
FIG. 11 is a rear elevation view thereof;
FIG. 12 is a right side elevation view thereof;
FIG. 13 is a left side elevation view thereof;
FIG. 14 is a top plan view thereof;
FIG. 15 is a bottom plan view thereof; and,
FIG. 16 is a front perspective view thereof, shown in a used condition on a shoe shown in broken lines.
The broken lines shown in the drawings illustrate environment in which the shoe jewelry is used that form no part of the claimed design.
